PADLOCK

Michael A. Yakubik, Hudson, Ohio, assignor to
The C. L. Gouger Machine Company, Kent,
Ohio, a corporation of Ohio

Application May 31, 1948, Serial No. 673,629

7 Claims. (CL 70—25)

1

This invention relates to improvements in a padlock.

An object of the present invention is to provide a pair of locking levers engaging suitable recesses in the legs of a shackle together with a locking plate normally held in locked position to prevent retraction of the locking levers, together with a vibrator controlled by a permutation lock adapted, upon proper manipulation, to move the locking plate to unlocking position, whereupon, the locking levers are released and the shackle may be freed from the padlock case.

Another object of the present invention is to so mount the vibrator with respect to one of the shackle legs that withdrawal of the shackle from the case automatically engages the vibrator to reset the permutation lock so that it is automatically in locked position when the shackle is pushed back into the case.

Another object of the present invention is to provide a novel mounting of the vibrator upon one of the locking levers with a portion of the vibrator adapted to be engaged by a portion of the shackle as the latter is removed from the case so that after the locking lever is released the vibrator is engaged to reset the lock.

Other objects and advantages of the present invention comprise the novel arrangement of a locking plate between the ends of the locking levers so as to normally hold them in locked position until the locking plate is released by proper movement of the vibrator, spring means for normally urging the locking levers to locked position, a novel combination between the vibrator and a permutation lock and other novel constructions, as clearly shown in the accompanying drawings and described in the specification, and the essential features of which will be set forth in the appended claims.

In the drawings,
Fig. 1 is a sectional view through one form of my improved lock and taken along the line 1—1 of Fig. 4, with a portion of a flat spring removed for a clearer understanding of the invention;

Fig. 2 is a fragmental sectional view of the same taken along the line 2—2 of Fig. 1;

Fig. 3 is a fragmental view partly in top plan and partly in section taken along the line 3—3 of Fig. 1, and showing the vibrator alone;

Fig. 4 is a sectional view taken along the line 4—4 of Fig. 1;

Fig. 5 is a view similar to Fig. 1 showing the position of the parts when the shackle is removed from the case and with a portion of the combination disc broken away;

2

Fig. 6 is a view showing the central portion of Figs. 1 and 5 with the parts in still another position corresponding to the locked padlock;

Fig. 7 is a view similar to the lower right-hand portion of Fig. 4;

Fig. 8 is a fragmental sectional view taken along the line 8—8 of Fig. 7, while

Fig. 9 is a fragmental sectional view taken along the line 9—9 of Fig. 5.

10 In the drawings, the padlock case is indicated at 10 and comprises a front cup-shaped portion 10a and a rear cover plate 10b. This is the working portion of the case which may be provided with an ornamental covering comprising a back piece 11 and a front cover 12, the rear edges of which are spun over at 12a upon the plate 11. A U-shape shackle 13 has a longer leg 13a passing through a support bracket 14, the opposite ends of which, as shown at 14a, Fig. 9, pass through suitable openings in the case portions 10a and 10b. A pin 15 in the leg of the shackle is adapted to pass through the opening 14b in the bracket support when the shackle is in the proper oriented position for the shorter leg 13b 15 to enter the opening 16 in the case. Another pin 16 is aligned with the pin 15 and has a rear portion 16a (Fig. 9) extending beyond the circular opening in support 14, through which shackle leg 13a passes, and this prevents the complete withdrawal of the shackle from the case in the unlocked position, as shown in Fig. 5. The shorter leg of the shackle 13b passes through the opening 16 in the case in the locked position, as shown in Fig. 1, and the movement of the shackle into the case is limited by the guard plate 17.

10 A pair of locking levers 18 and 19 are pivotally mounted in the case portion 10a by means of the shoulder rivets 20. The upper ends of these levers are provided with nose portions 18a and 19a respectively, which are strengthened by in-turned flange portions 18b and 19b respectively. The shackle legs are provided with recesses 21 and 22 respectively, into which the locking lever noses 18a and 19a respectively, are adapted to enter in the locked position shown in Figs. 1 and 6. Means is provided for normally urging these noses of the locking levers into their associated recesses, and this comprises a tension spring 23 which is held between the lower ends of levers 18 and 19, as best shown in Figs. 1 and 5. Means is provided for normally preventing the movement of shackle 13 out of the case because, obviously, a pull upon the shackle in the position of the parts shown in Fig. 1 would cause the cam surfaces of recesses 21 and 22 to cam the locking

levers toward each other to release the shackle. To prevent this, a locking plate 24 is normally held by a spring 25 in the position shown in Fig. 6 where the ends of the locking plate abut the flanges 18b and 19b to prevent retraction of the locking lever noses out of the shackle recesses. This locking plate is mounted on a pivot shaft 26, the ends of which are held in the case. As best seen in Fig. 4, the side portions of the locking plate are bent upwardly as shown at 24a, to pass over the top of shaft 26, and the mid portion of the plate is bent downwardly as shown at 24b, to pass beneath the bottom of the shaft 26. The spring 25 has one end held against a stop 27 on the case and is then looped once or twice around shaft 26, as best seen in Fig. 4, and the opposite end of the spring rests against the right-hand end of the locking plate, as clearly seen in Figs. 1 and 5. This normally urges the locking plate in a clockwise direction, as viewed in Figs. 1, 5 and 6, and this motion is limited by the shoulder 28 on the locking lever 19.

The means provided for moving plate 24 out of its locking position comprises a vibrator 29 which is pivotally mounted by means of pivot 30 on the upper end of lever 18. The construction of pivot 30 is best seen in Fig. 2. This comprises a pin 30a riveted to the vibrator 29. This pin enters a cup-shape bearing 31 which is riveted to lever 18. A flat spring 32 is riveted to the case by rivet 33. This spring presses against the vibrator 29 and holds it in the position shown in the various views. On the end of the vibrator opposite the pivot 30 is mounted a tapered pin 34, the inner end of which is adapted to coact with a permutation lock whereby the vibrator is manipulated.

The permutation lock here described is similar to that shown in Patent Number 2,308,892, granted January 19, 1943, to Edward M. Miller, but obviously, other types of combination locks might be used for the control of vibrator 29. The type here shown comprises a disc 35 which is an integral part of a shaft 36 which extends through the front wall of the case and is provided with a knob 37 for manipulation of the lock. On the disc 35 are various cams, as shown at 35a, 35b, 35c, and 35d. This is a known form of permutation lock for working the pin 34 gradually from the center of disc 35 outwardly to the final unlocking position shown in Fig. 1. Referring to Fig. 6, in one type of manipulation the pin 34 is carried outwardly to the pointed end of cam 35a by rotation of disc 35 in a clockwise direction. Then, upon counterclockwise rotation of disc 35, the pin 34 remains in fixed position relative to disc 35 because of spring 32, until cam 35b engages pin 34 in the position shown in Fig. 6 and, as disc 35 rotates in a counterclockwise direction the cam 35b works pin 34 radially outwardly. When pin 34 has been moved out as far as possible by cam 35b, disc 35 is again rotated in a clockwise direction (pin 34 remaining where it is) until cam 35c engages pin 34 to again move it radially outwardly. At the conclusion of this operation, disc 35 is again rotated in a counterclockwise direction until cam 35d engages pin 34 and carries it to the position of Fig. 1. This causes the nose 29a of the vibrator to engage the right-hand end of locking plate 24, as viewed in Fig. 1, rotating the locking plate in a counterclockwise direction so that it no longer lies between the locking lever flanges 18b and 19b. It is then possible to pull outwardly on shackle 13 causing the cam surfaces of recesses

21 and 22 to move the lever noses 18a and 19a respectively, inwardly to the position shown in Fig. 5, releasing the shackle.

Means is provided for automatically resetting the lock when the shackle is pulled to its outward position, as shown in Fig. 5. Referring for a moment to Fig. 1, it will be noted that the vibrator 29 has a flanged end 29b which extends farther to the left than the nose 18a of the locking lever 18. It results from this construction that as shackle 13 is moved from the position of Fig. 1 to that of Fig. 5, the recess surface 21 first cams the nose 18a out of the way, and then engages the nose 29b of the vibrator causing a counterclockwise movement of the vibrator about pivot 30 from the position of Fig. 1 to that of Fig. 5. This automatically throws the pin 34 back into the maze of the permutation lock so that when the shackle is again moved inwardly from the position of Fig. 5 to that of Fig. 1, it is automatically locked in that position, as first described.

The disc 35 is provided with the usual notches 38 in which engages a spring 39 held by member 40 on the case 10 so that as knob 37 is manipulated the operator is apprised by clicks of the extent of oscillation of disc 35. Those skilled in this art will understand that beginning with the pin 34 against the nose of cam 35a the operator is given a certain number of clicks alternately toward the right or left so as to work the pin 34 through the cams 35b, 35c, and 35d to unlocking position, as previously described.

As shown in Figs. 7 and 8, there may be provided a stop ring 41 intermediate between knob 37 and shaft 36 for the purpose of providing more turns of the knob in working the combination as is fully described and claimed in the copending application of Edward M. Miller, Serial Number 666,661, filed May 2, 1946, which is now Patent Number 2,441,895, granted May 18, 1948, to which reference may be had for an understanding of this modification. The present lock may use this Miller invention or not, as desired.

What I claim is:

1. In a padlock, a case, a U-shape shackle having two legs adapted to enter said case, two locking levers pivotally mounted in said case, there being recesses, one in each of said shackle legs for receiving its associated locking lever, a locking plate supported in said case, means normally urging said plate to locking position relative to said levers and preventing removal of the latter from said recesses, a vibrator movable to a position for holding said plate in unlocking position to permit removal of said levers from said recesses, and a permutation lock in said case for controlling said vibrator.

2. In a padlock, a case, a U-shape shackle having two legs adapted to enter said case, there being recesses provided, one in each of said shackle legs, said recesses being positioned opposite each other, two locking levers pivotally mounted in said case and having locking ends in position to engage said recesses when said shackle legs enter said case, said locking ends being movable toward and away from each other by lever oscillation, a locking plate movably supported in said case between said locking ends, means normally urging said plate to locking position between said locking ends where it prevents removal of the latter from said recesses, a vibrator movable to a position for holding said plate in unlocking position to permit removal of said lever locking ends from said recesses, and a permuta-

tion lock in said case for controlling said vibrator.

3. The combination of claim 1 including means operable by movement of said shackle away from said case for moving said vibrator out of plate-holding position.

4. The combination of claim 2 wherein said vibrator is pivotally mounted on one of said locking levers and a portion of said vibrator, when the latter is in said position holding said plate in unlocking position, is so located that movement of said shackle away from said case operatively engages said vibrator to move said vibrator out of said plate-holding position.

5. In a padlock, a case, a U-shape shackle having two legs adapted to enter said case, two locking levers pivotally mounted in said case, there being recesses, one in each of said shackle legs for receiving its associated locking lever, a locking plate supported in said case, means normally urging said plate to locking position relative to said levers and preventing removal of the latter from said recesses, a vibrator movable to a position for holding said plate in unlocking position to permit removal of said levers from said recesses, said vibrator being provided with a pivotal mounting intermediate its ends, a permutation lock in said case engaging one end of said vibrator and adapted to move said vibrator to said plate-holding position by operation of said lock, the other end of said vibrator, when said vibrator is in plate-holding position overlying a portion of said shackle in position to be engaged thereby as said shackle is moved away from said case, whereby upon opening of said padlock said one end of said vibrator is returned to a position corresponding to locking position of said plate.

6. In a padlock, a case, a U-shape shackle having two legs adapted to enter said case, there being recesses provided, one in each of said shackle legs, said recesses being positioned oppo-

site each other, two locking levers pivotally mounted in said case and having locking ends in position to engage said recesses when said shackle legs enter said case, said locking ends being movable toward and away from each other by lever oscillation, a locking plate movably supported in said case between said locking ends, means normally urging said plate to locking position between said locking ends where it prevents removal of the latter from said recesses, a vibrator having a pivotal mounting intermediate its ends on one of said locking levers adjacent the locking end thereof, one end of said vibrator being movable to a first position for holding said plate in unlocking position to permit removal of said lever locking ends from said recesses, the other end of said vibrator in said first position extending into one of said recesses whereby said vibrator is oscillatable by movement of said shackle away from said case to move said vibrator out of said first position, and a permutation lock in said case for controlling said vibrator.

7. The combination of claim 2 wherein stop means is provided on one of said locking levers for preventing movement of said locking plate beyond locking position under influence of said urging means.

MICHAEL A. YAKUBIK.
